HEEL

Frederick R. Keith, Randolph, Mass.

Application November 24, 1934, Serial No. 754,652

8 Claims. (Cl. 36—35)

The present invention relates to shoe heels, and more particularly to shoe heels of the resilient or rubber type.

In spite of the fact that resilient or rubber heels are more popular than are leather heels and are much more frequently found on shoes today, in one respect rubber heels are less satisfactory than are leather heels. If a new shoe provided with a leather heel be placed upright by itself on a flat surface, almost invariably the entire bottom of the heel and a portion of the sole engage that flat surface. If, however, a new or newly repaired shoe provided with a rubber heel be so placed on a flat surface, almost invariably the only portion of the heel which engages the flat surface is the portion in the vicinity of the bottom of the breast. Stated in another way, viewing such a shoe from its side, a rearwardly widening, wedge-shaped gap will be seen bounded by the tread surface of the heel and the surface upon which the heel rests. This construction causes the heel to be pivoted on the breast region of its bottom. By pressing down upon the back of the shoe, the entire shoe may be rocked backward on the heel breast region as a pivot until the entire bottom of the heel engages the supporting surface, causing the entire sole to rise above such surface and completely clear it. If the pressure on the back of the shoe be then released, the shoe will tilt forward on its heel breast pivot, the sole will be lowered into contact with the support, and there will again appear the wedge-shaped gap formed by the heel and the support.

If, now, the wearer stands in his shoes, his weight causes the wedge-shaped gap to disappear, or nearly so. Stated in another way, the force of the wearer's weight causes the heel to be compressed so that all or nearly all of its tread surface engages the ground. But it is to be particularly noticed here that this compression is not uniform. Instead, it is greatest in the vicinity of the breast of the heel and decreases rearwardly. This greatest compression in the vicinity of the breast has a most important effect upon the comfort with which the shoe heel supports the heel of the foot.

It was intended by nature that when a person stands on both feet, the full force of his weight should, fundamentally, be distributed between and supported by the ball and the plantar tubercles of the os calcis or bottom of the heel bone of each foot. When a person stands in his bare feet this is precisely what occurs if his feet are normal. As a matter of anatomy, in advance

of the plantar tubercles of the os calcis there is a rise in the bony structure, forming part of the longitudinal arch of the foot. It was never intended by nature that this rise and the flesh beneath it should be a base or terminal support for the weight of the body, that is, should be a substitute for the plantar tubercles of the os calcis—but in the wearing of shoes provided with rubber heels such a substitution does take place.

If a shoe be examined in connection with the anatomy of the human foot, it will be seen that the breast of the shoe heel lies well forward of that portion of the body of the shoe heel which underlies the plantar tubercles of the os calcis when the shoe is worn. In fact, it will be seen that the breast region of the heel lies beneath the rise of the longitudinal arch of the foot which is in advance of the plantar tubercles. From these observations on heel compression and shoe and foot structure, it follows that when a person stands in shoes provided with rubber heels, the principal reason why support is given the plantar tubercles directly is that the portion of the foot which underlies the rise of the arch in advance of the plantar tubercles presses down so hard upon and compresses the breast region of the rubber heel as to bring the tread surface portions thereof which lie behind the breast region down into contact with the ground.

The unhealthy situation presented by such shoe construction is obvious. The weight of the body is thrown directly upon a part of the foot never intended to support that weight directly, and strains and aches result. The harm of this great compression of the breast region of a rubber heel can be easily appreciated by stamping the feet so that the heel and sole strike the ground simultaneously. The compression of the breast region of the heel can be plainly felt in this experiment, and so can the sting or pain resulting from it. Such compression and its effects, differing only in degree from the results of stamping the feet, occur with every step a wearer takes throughout the day.

With a view to correcting this situation, it is the principal object of the present invention to provide a resilient or rubber shoe heel by the use of which the force of the wearer's weight is directed downward properly through the planar tubercles of the os calcis, the portion of the heel which nature intended should receive and support the wearer's weight. Stated in another way, it is the principal object of the present invention to provide a resilient or rubber shoe heel of such nature that it supports the human heel when in

a shoe in a manner substantially identical with that in which the ground supports the human heel when no shoe is worn.

To the accomplishment of this object and such others as may hereinafter appear, the various features of the present invention reside in certain constructions, combinations, and arrangements of parts fully described hereinafter and then pointed out in their true scope in the appended claims.

The various features of the present invention will be readily understood from an inspection of the accompanying drawing, illustrating the best form of the invention at present known to the inventor, in which,

Figure 1 is an underside plan of my heel construction;

Fig. 2 is a front (breast) elevation, showing the heel secured to the heel base of a shoe;

Fig. 3 is a vertical section taken along the line 3—3 of Fig. 2;

Fig. 4 is a side elevation of a shoe provided with an ordinary rubber heel, the shoe being shown resting by itself upon a flat surface; and

Fig. 5 is a side elevation of the shoe illustrated in Fig. 4, but showing it tilted back to cause the entire tread surface of the heel to engage the supporting surface.

Referring to the drawing, the illustrated embodiment of the present invention comprises a heel body 7 which is preferably made of some suitable rubber compound, though other suitable resilient materials may be used, and is provided with the usual nail holes 8 and nail-anchoring washers 9 for receiving nails 10 by which it is secured to the heel base 11 (Figs. 2 and 3) of a shoe. Except for the region in the vicinity of the breast 13, in the formation of which region my invention lies, the heel may be formed from its attaching surface 14 through to its tread surface 15 in the usual solid manner, attention being called to the fact that this is true of the back of the heel, which strikes the ground first in walking, and is also true of the more or less central area or region A which underlies the plantar tubercles of the os calcis of the wearer.

Having particular regard to Figs. 1, 2 and 3, it will be seen that in the vicinity of the breast 13 a portion of the heel body is removed or cut away from the tread surface 15, leaving an arch 16 which extends downward transversely of the heel, as shown in Fig. 2, from a central breast point above the plane of the tread surface 15, and terminates short of the opposite ends of the breast 13 so as to leave narrow, tread surface portions or runs 17 and 18 at the opposite end portions of the breast. As shown in Fig. 3 the arch 16 also extends downward longitudinally of the heel from the breast 13, and terminates rearwardly at the tread surface 15 at a point marking the forward limit of the central region A. It will be appreciated that since the arch 16 is an arch of the type stated, its line of merger with the tread surface 15 comprises an arcuate edge 19 which causes the runs 17 and 18 to flare rearwardly. As shown in Figs. 2 and 3, the arcuate edge 19 is preferably rounded or convex and is not sharp. Stated in another way, the arch 16 is itself slightly concave, but gradually merges into the tread surface 15 along an arcuate, convex edge 19. By reason of this construction the tread surface (Fig. 1) is, in effect, yoked at its breast end, the yoked ends being the breast region runs or portions 17 and 18 of the tread surface 15.

As indicated in Figs. 1, 2, and 3, the arch 16 comprises a surface separate from, but merging with, the tread surface, and the separate surface or arch 16 is disposed above the plane of the tread surface 15. The arch 16 may be cut or gouged from a solid heel, or the entire heel may be molded so as to form the arch 16. As a commercial matter, it is obvious that molding is the preferable method of manufacture.

With this construction, it will be seen that whereas the body 7 of the heel has a normal or given resiliency, the tread portions or runs 17 and 18 have a greater than normal resiliency, decreasing in the direction of the back of the heel. This increase in resiliency is caused by the fact that the body material between the runs 17 and 18 has been removed, allowing for lateral expansion in two directions under pressure, which would not be the case if the entire breast region of the heel extended down to the tread surface 15.

To consider Figs. 4 and 5, it has been stated above that Fig. 4 illustrates a shoe provided with a rubber heel 20 of ordinary construction, i. e., with no part of its breast portion removed. Figure 4 brings out that when such a shoe rests upon a flat surface 21, the breast region 22 is a pivot, behind which there is a rearwardly widening wedge-shaped gap B. The shoe may be swung back on the pivot 22 to the position shown in Fig. 5, in which case the gap B disappears, the entire tread surface of the heel engages the surface 21, and the sole 23 clears the surface 21.

If a person stands in shoes such as shown in Figs. 4 and 5, the breast region or pivot 22 is flattened and compressed under the influence of the wearer's weight, and the portions of the tread surface which lie behind the pivot 22 are forced against the ground, causing the gap B to disappear, or nearly so, depending upon the weight of the wearer. But it is to be particularly noticed in this connection that this compression of the pivot 22 is not caused by the rearward rocking transition from Fig. 4 to Fig. 5, because when a person stands in his shoes the soles thereof engage the ground as well as the heel. Instead, this compression of the pivot 22 is caused by the fact that the weight of the body acts downward through the leg and ankles along a line lying more or less over the breast or pivot region 22 of the heel. Since the plantar tubercles of the os calcis lie behind this breast or pivot region 22, it follows that the weight of the body does not and can not act directly through the plantar tubercles to compress the breast or pivot regions 22. Instead, this compression is caused directly only by the weight of the body acting through the bony arch portion and the underlying flesh which lie forward of the plantar tubercles. As a consequence the weight of the body causes abnormal pressure and strain on portions of the foot which nature never intended should be subjected to such pressure and strain, and the aches and pains and general discomfort which people experience as the result of being on their feet are directly traceable to a great extent to this shoe and rubber heel construction.

In view of the nature of my heel it will be seen that the weight of the body is properly supported by the plantar tubercles of the os calcis whether a person is standing still or is walking, and that the bony arch portion and the flesh in advance of the plantar tubercles are not called upon to support the weight of the body directly. When a person stands in shoes provided with resilient

heels such as I have disclosed, the breast region of the tread surface 15 compresses under a relatively small amount of pressure because that tread surface breast region comprises only the 5 two narrow runs 17 and 18 at the opposite ends of the breast region and therefore has greater resiliency than has the rest of the heel. As a consequence, the weight of the body is borne almost entirely by the plantar tubercles of the os calcis of each foot, that is, is borne almost entirely by the central area or region A (Figs. 1 and 3) of the shoe heel and not almost entirely by the breast region as would be the case if the entire breast region extended down to the plane 10 of the tread surface 15.

In walking, a similar situation appears, varied only by the fact that the direction of the force of the wearer's weight shifts from the back to the breast of the heel as the wearer first strikes 15 the ground with the back of his heel and then continues the movement of his step until the heel leaves the ground. After the initial striking 20 of the back of the heel against the ground, the entire tread surface of the heel next contacts the ground. At this precise moment the sole is 25 still clear of the ground and the weight of the body is not yet forward enough to cause appreciable compression of the heel breast region. Stated in another way, at the instant before the 30 wearer's weight is directly over the breast region of his heel, the weight of the body is supported by the central area or region A. As the body continues to move forward, the weight of the wearer is next directly over the breast region 35 and is then supported by both the breast region and the sole. In these last two phases the runs 17 and 18 are considerably compressed just as the breast region of an ordinary rubber heel is compressed in the same phases. But it is to be 40 noticed that since the runs 17 and 18 are more resilient than the rest of the heel, they compress under much less pressure. Stated in another way, the runs 17 and 18 have relatively little resistance 45 to compression and therefore yield readily under the wearer's weight. The bony arch rise and the underlying flesh which overlie the breast region and in advance of these plantar tubercles thus do not bear the brunt of the wearer's 50 weight.

The arch 16 lies in advance of the portion of the area or region A which directly underlies the plantar tubercles of the os calcis so that when the heel and the sole of the shoe simultaneously engage the ground, the plantar tubercles will have an equally firm support in all directions. Since the arch 16 merges with the forward portion of the area or region A of the tread surface 15, and rises in the direction of the breast, it will be seen that the resiliency of the runs 17 and 18 increases in the direction of the breast, being greatest at the breast and reduced to an amount equal to that of the body of the heel where the runs 17 and 18 merge with the central area or region A. With this construction, as the weight 60 of the wearer shifts from the central area or region A to a point over the breast region, the breast region gives to an increasing degree, and the convexity of the edge 19 aids in imparting a 65 smooth continuity to this yielding.

While I have shown the surface 16 to be both transversely and longitudinally arch shaped so as to provide an arcuate edge 19 and therefore two tread surface runs 17 and 18 at opposite 70 ends of the breast region, I wish to point out

that I do not wish to be limited to these details of construction. The surface 16 might be more or less rectangular or triangular in appearance, viewing Fig. 1, without destroying the breast region resiliency which my construction achieves. 5 In a similar manner, it is not necessary that the runs 17 and 18 lie at the opposite ends of the breast portion of the heel since they may be spaced therefrom without destroying their yielding function. It is preferred, however, to locate 10 the runs 17 and 18 as shown because this construction simulates the appearance of the sides of an ordinary heel.

Looking at my improved heel in a different light, I have disclosed it as being of solid rubber throughout. I wish to point out, however, that the present invention is well adapted for use with heels provided with a central screen or with a plate such as disclosed in my Patent No. 1,426,- 15 198, August 15, 1922. The surface 16 and the thread surface runs 17 and 18 do not interfere with the use of such a screen or plate, and in fact improve a rubber heel so provided. Moreover, my improved heel has been illustrated in 20 Figs. 2 and 3 as secured to the heel base 11 of a shoe for the purpose of avoiding any confusion that might arise from a showing of a heel provided with a scooped or rand effect attaching surface. When a heel is secured to its heel base, 25 such attaching surfaces assume the planiform appearance indicated for the attaching surface 14 in Figs. 2 and 3, and as such attaching surfaces form no part of my invention, they have not been shown. It should be pointed out, however, 30 that as with the internal screen or plate, the arch 16 and the tread surface runs 17 and 18 may be used on a heel having a scooped or rand effect attaching surface, and it is in fact contemplated that they should be so used.

What is claimed as new is:

1. A heel for a shoe comprising a resilient body portion, and a second body portion having a resiliency greater than that of the first body portion, said first body portion extending forwardly 45 from the back of the heel and terminating in an area adapted to underlie the plantar tubercles of the os calcis, said second body portion extending from one side of the heel to the other at its breast and also extending rearwardly from the breast to merge with said first body portion at said area, the greater resiliency of said second body portion 50 decreasing rearwardly to a condition of equality with that of said first body portion at said merging area.

2. A heel for a shoe comprising a resilient body portion provided with a tread surface, and a second body portion having a resiliency greater than that of the first body portion and provided only partially on its under side with a tread surface, 55 said tread surfaces lying in a plane, said first body portion extending forwardly from the back of the heel and terminating in an area adapted to underlie the plantar tubercles of the os calcis, said second body portion extending in its entirety 60 from one side of the heel to the other at its breast and extending rearwardly therefrom to merge with said first body portion at said area, the tread surface of said second body portion merging at said area with the tread surface of said first body portion, the part of the under side of said second body portion not provided with a tread surface 65 being spaced above the plane of the tread surfaces from the breast to said merging area, and the greater resiliency of said second body portion 70 decreasing rearwardly to a condition of equality 75

with that of said first body portion at said merging area.

3. A resilient heel for a shoe provided with a yoked tread surface and with a second surface disposed above the plane of said tread surface, said second surface extending transversely of the heel between the tread-surfaced portions formed by the yoking and also extending longitudinally of the heel between the breast thereof and the portion of the tread surface marking the termination of the yoking, said tread surface and said second surface merging into each other along a convex edge all portions of which lie in advance of that part of the tread-surfaced portion adapted to underlie the plantar tubercles of the os calcis.

4. A resilient heel for a shoe comprising a tread-surfaced body portion adapted to support that part of the wearer's weight which is directed through the plantar tubercles of the os calcis, spaced tread-surfaced portions extending rearwardly from the breast of the heel and merging with said body portion at points in advance of that part thereof adapted to underlie said plantar tubercles, and a body portion, merging with all of said tread-surfaced portions, disposed above the tread surface.

5. A heel for a shoe comprising a resilient tread-surfaced portion, other tread-surfaced portions having a resiliency greater than that of said first portion, the tread surfaces of said portions lying in a plane, and an additional portion, said first portion being adapted, in part, to underlie the plantar tubercles of the os calcis, said other tread-surfaced portions comprising spaced runs extending rearwardly from the breast of the heel to points of merger with said first portion, said points of merger being in advance of that part of the first portion adapted to underlie said plantar tubercles, the resiliency of said runs decreasing rearwardly to a condition of equality with that of said first portion at said points of merger, and said further portion being integral with said tread-surfaced portions and overlying the space between said tread-surfaced runs, the under surface of said further portion merging with said tread-surfaced portions at said area of merger but being otherwise spaced therefrom and lying above the plane of said tread surfaces.

6. A heel for a shoe comprising a resilient tread-surfaced portion, other tread-surfaced portions having a resiliency greater than that of said first portion, the tread surfaces of said portions lying in a plane, and an additional portion,

said first portion comprising the greater part of the body of the heel and being adapted, in part, to underlie the plantar tubercles of the os calcis, said other tread-surfaced portions comprising spaced runs extending rearwardly from the breast of the heel to an area of merger with said first portion, said runs being narrowest at the breast of the heel and increasing in width in the direction of said area of merger, said area of merger lying in advance of that part of the first portion adapted to underlie said plantar tubercles, and said further portion being integral with said tread-surfaced portions and overlying the space between said tread-surfaced runs, the under surface of said further portion merging with said tread-surfaced portions at said area of merger but being otherwise spaced therefrom and lying above the plane of said tread surfaces.

7. A heel for a shoe comprising a resilient body portion having an attaching surface and a tread surface a portion of which is adapted to underlie the plantar tubercles of the os calcis, and a second body portion having an attaching surface extending from one side of the heel to the other at its breast and merging rearwardly with the first named attaching surface, said second body portion also having spaced runs provided with tread surfaces, respectively, which extend rearwardly from the breast of the heel and merge with the first named tread surface at points in advance of that portion thereof adapted to underlie said plantar tubercles, the part of the second body portion located between said runs and beneath the attaching surface having an under surface located above the plane of the tread surfaces of said runs and extending transversely therebetween, said under surface terminating rearwardly at the tread surface of the first body portion.

8. A resilient heel for a shoe comprising a tread-surfaced body portion adapted to support that part of the wearer's weight which is directed through the plantar tubercles of the os calcis, spaced tread-surfaced portions extending rearwardly from the breast of the heel and merging with said body portion at points in advance of that part thereof adapted to underlie said plantar tubercles, the tread surfaces of all of said portions lying in a plane, and a portion disposed above the plane of said tread surfaces, said portion extending across the heel at the breast from one of said spaced tread-surfaced portions to the other and extending rearwardly from the breast to merge with said body portion at its tread surface.

FREDERICK R. KEITH. 55
